UNITED STATES PATENT OFFICE.

WILLIAM H. WARD, OF BOSTON, MASSACHUSETTS; HENRY H. COTTON
EXECUTOR OF SAID WARD, DECEASED.

WATER-CLOSET VALVE.

SPECIFICATION forming part of Letters Patent No. 449,769, dated April 7, 1891.

Application filed September 3, 1889. Serial No. 322,882. (No model.)

To all whom it may concern:

Be it known that I, WILLIAM H. WARD, of Boston, in the county of Suffolk and State of Massachusetts, have invented certain new 5 and useful Improvements in Water-Closet Valves, of which the following is a specification.

This invention has for its object to provide a valve for water-closet supply-tanks having 10 improved means by which it shall be retarded in its closing movement by an air-cushion and allowed to close at any desired rate by the escape of the air forming said cushion through an adjustable vent or orifice.

15 The invention comprises the detail construction, combination, and arrangement of parts, substantially as hereinafter fully set forth, and particularly pointed out in the claims.

20 Of the accompanying drawings, forming a part of this specification, Figure 1 represents a vertical section of my improved valve and a part of the bottom of a tank to which it is applied, the valve being closed. Fig. 1^a represents 25 a perspective view of the air-valve. Figs. 2 and 3 represent similar views, the valve being raised, Fig. 2 showing the conditions when the valve is being raised, while Fig. 3 shows the conditions when the valve is 30 descending. Figs. 4 and 5 represent sectional views of modifications.

The same letters of reference indicate the same parts in all the figures.

In using the term "valve" in this specification it will be understood that I refer to the part that is seated upon the outlet-pipe and directly controls the escape of water, while by the term "air-valve" I mean the valve that admits air to the air cup or chamber.

40 In the drawings, *a* represents the bottom of a water-closet supply-tank, and *b* the outlet-pipe or fitting secured thereto in any suitable way and provided with a seat *c* for the valve *d*. Said valve may be of any suitable construction. In Figs. 1, 2, and 3, which I will first describe, I have shown it made in one piece with the inverted cup or chamber *e*, which contains the air-cushion, the valve being the lower end or mouth of said cup.

45 *f* represents the fixed part which constitutes the bottom of the air-chamber within

the cup *e*, said part being a circular head or piston snugly fitting the interior of the cup *e* and connected by vertical standards 22 with a screw-threaded ring 3, which is screwed into 55 the valve-seat or escape-pipe fitting. When the valve *d* and cup *e* are raised, an air-space is formed between the fixed head *f* and the top of the cup *e*, air being admitted to said space from a point above the water in the 60 tank through a pipe *h*, which is affixed to the cup and extends upwardly, so that its upper end is above the highest level the water can attain in the tank. In the upper end of said pipe is an air-inlet *i*, at the inner end of which 65 is a valve-seat *j*.

k represents the air-valve, which is located in the pipe *h* between the seat *j* and a fixed collar or support *m*, and is adapted to play between said seat and collar. The air-valve 70 is formed at its upper end to fit said seat and close the air-inlet when raised by air-pressure within the pipe. Said air-valve is provided with one or more grooves *h'*, (see Fig. 1^a), which permit air to pass around the air-valve 75 when the latter rests on the collar *m*. In the upper portion of the pipe *h*, below the air-inlet, is a branch, in which is an air-outlet *o*, having a screw *P*, which adjusts the size of the 80 outlet-passage.

From the foregoing it will be seen that when the valve *d* is closed, as shown in Fig. 1, the air-valve *k* rests on the collar *m* and permits the passage of air around it, so that when the valve *d* is being raised the air will enter at 85 the inlet *i* and pass downwardly around the air-valve *k* through the pipe *h* into the cup *e*, as indicated by the arrows in Fig. 2. When the valve is released and commences to fall, the air-pressure raises the air-valve *k* to the 90 seat *j*, as shown in Fig. 3, thus closing the air-inlet *i*, so that air can escape only through the outlet *o*, the air passing from the cup *e* through the pipe *h* to the air-outlet, as indicated by the arrows in Fig. 3. The valve *d* 95 can therefore fall only as fast as the air-cushion formed in the cup *e* by the raising of the valve is reduced by the escape of air through the outlet *o*, and said escape can be made as slow as may be desired by adjustment of the 100 screw *P*.

In Figs. 1, 2, and 3 I show a stand or over-

flow pipe *q*, attached to the cup *e*, the latter having double walls, between which is a space *r*, communicating with the stand-pipe. The inner wall of the cup has ports *s s*, through 5 which water entering the stand-pipe will flow out into the discharge-pipe.

To limit the upward movement of the valve *d* and cup *e*, I provide the fixed head *f* with an upwardly-projecting stud *g*, extending into 10 the pipe *h* and provided within the latter with a head *g'*, which, by engaging a shoulder *g''* in the pipe *h*, prevents the cup from being lifted above the head *f*. Said stud is made tubular, so that air can pass through it, as 15 indicated in the drawings. Any other suitable stop may be substituted for the stud.

In Fig. 4 I have shown a construction similar to that already described, excepting that the cup is not provided with a stand-pipe, a 20 fixed stand-pipe *q'* being connected with the outlet pipe or fitting at one side of the valve.

In Fig. 5 the cup is located above the water in the tank and attached to a rod *u*, passing through a fixed cross-bar *v* above the water-line. The fixed part or head *f*, that constitutes 25 the bottom of the air-space within the cup *e*, is affixed to said cross-bar. In this modification the valve is pivoted or loosely connected to the lower end of the rod *u*, and the air-30 valve *k* is on the under side of the top of the cup. The air-outlet may be arranged as previously described or in any other suitable manner.

The head *f*, the vertical standards 22, and 35 the screw-threaded ring 3 are cast in one piece and constitute what I term a "cage," the head *f* being the top of the cage. The outlet-fitting *b* has an internal screw-thread within the valve-seat *c*, and the threaded ring of said 40 cage is screwed into said shoulder, as shown. The cage is therefore within the circle of the valve-seat and is easily attached to and removed from the outlet-fitting.

I claim—

45 1. The combination, with the outlet-fitting, of the fixed part or head secured thereto and projecting upwardly therefrom, the cylindrical valve, the inverted cup secured thereto and located therein and inclosing said fixed

part or head and having an upper pipe *h*, 50 provided with an inlet and an outlet at its upper end, substantially as set forth.

2. The combination, with the outlet-fitting, 55 of the fixed part or head secured thereto and projecting upwardly therefrom, the cylindrical valve seated at its lower end on said outlet-fitting, the inverted cup secured to said valve and located therein and inclosing said fixed part or head, the upper pipe *h*, projecting from said cup and having upper and lower valve-seats in its upper end, and a movable or sliding air-inlet valve, substantially as set forth.

3. The combination, with the outlet-fitting, 60 of the fixed part or head secured thereto and projecting upwardly therefrom, the cylindrical valve seated at its lower end on said outlet-fitting, the inverted cup secured to said valve and located therein and inclosing said fixed part or head, the upper pipe *h*, projecting 65 from said head and having a lower shoulder *g''* and upper and lower valve-seats in its upper end, the movable or sliding air-inlet valve, and the pipe *g*, projected from said fixed part or head and having an upper enlarged end located in said pipe *h* and designed 70 to engage said shoulder *g''*, as set forth.

4. The combination of the valve, the inverted cup attached thereto and provided with the upwardly-projecting pipe *h*, the air-inlet 75 valve and the adjustable air-outlet in the upper portion of said pipe, and the fixed head *f*, attached to the outlet-fixture and located in the inverted cup as a bottom for the air-chamber therein, and the fixed stud attached to 80 the head *f* and provided within the pipe *h* with a head or enlargement, whereby removal of the valve from the head *f* is prevented, as 85 set forth.

In testimony whereof I have signed my 90 name to this specification, in the presence of two subscribing witnesses, this 9th day of May, A. D. 1889.

WILLIAM H. WARD.
